Primary Examiner—Stella Reid
Attorney, Agent, or Firm—Bielen, Peterson & Lampe[57] **CLAIM**

The ornamental design for a slide device for testing and displaying fertility determinations, as shown and described.

DESCRIPTION

FIG. 1 is a top plan view of first embodiment the viewing section of a slide device for testing and displaying fertility determinations showing our new design;

FIG. 2 is a top plan view of a second embodiment of the viewing section of a slide device for testing and displaying fertility determinations showing our new design;

FIG. 3 is a bottom plan view of the embodiments of FIGS. 1 and 2;

FIG. 4 is a top plan view of the testing section;

FIG. 5 is a bottom plan view of the testing section of FIG. 4;

FIG. 6 is a top plan view of the combined viewing and testing sections rotated 60° from one another;

FIG. 7 is a bottom plan view of the combined viewing and testing sections of FIG. 6;

FIG. 8 is a front elevational view of the combined viewing and testing sections of FIGS. 6 and 7 in congruent orientation, the left and right side views being identical thereto;

FIG. 9 is a front elevational view of the viewing and testing sections of FIGS. 1-5, the left and right side views being identical thereto; and,

FIG. 10 is a rear elevational view of the viewing and testing sections of FIGS. 1-5.
